UNITED STATES PATENT OFFICE

WILLIAM HORWITZ, OF BROOKLYN, NEW YORK

INCUBATOR

Application filed December 14, 1926. Serial No. 154,673.

The improvements relate primarily to incubators, for hatching eggs, but are applicable to other devices of this general class. Their nature and objects will be more fully set forth in the description of the exemplary embodiment illustrated in the accompanying drawings, referred to herein, and in which—

Fig. 1 is a side elevation of an incubator embodying the improvements;

10 Fig. 2 is a top plan view of the same;

Fig. 3 is an end view;

Fig. 4 is a bottom plan view with some parts broken away;

15 Fig. 5 is an enlarged detail in perspective showing the ventilators, moistener and adjacent parts, detached;

Fig. 6 is a vertical cross section substantially on the line 6—6 of Fig. 5.

The outer frame or housing 1 of the incubator may be of any satisfactory form, construction and material, and provided with transparent windows 2, 3 and 4 giving a view of the interior. It is preferably mounted on legs 5 and 6. On one end of this frame is supported a heater 7, comprising a lamp and heating coil communicating with the interior of the incubating compartment and the moistener through pipes 8, 9 and 10 for conveying and maintaining a circulation of heating fluid.

20 A damper 11 is provided at the top of the heater. The tube 8 communicates with a heating pipe 12 extending around the top of the compartment and having cross pipes 13, so that an even distribution of the heat throughout the upper part of the compartment is insured. A vent 14 is located at the top of the housing, to permit the escape of air and other gases from the compartment, and this vent is controlled by a shutter 15.

25 At the end of the box or housing opposite the heater the pipe 9 extends outwardly and downwardly to communicate with the heating tube 16, extending through the moistening trough 17, and this pipe on the exterior of the housing is insulated and protected by a wrapping of cork 18 and an exterior layer of asbestos 19 enclosed in a box of wood or other suitable material 20, so that it will be thoroughly protected against heat radiation and will insure that the heating fluid passing

downwardly therethrough will reach the bottom without substantial loss of temperature from heat radiation. The pipe 9 is narrowed, as shown at 9' at its upper end, where it is connected by a union 9'', with the heating tubes 12, etc.

30 The trough 17 is secured to the bottom of the box 1, is insulated by a surrounding layer of asbestos or similar non-conductor of heat 21, and is housed in an elongated box 22. Water is supplied thereto through the pipe 23 having a funnel shaped upwardly turned end on the exterior of the incubator, so that water may be supplied thereto without opening the doors and thereby admitting air to the egg compartment. The level of water may be observed through the funnel shaped mouth of the pipe, and may be maintained therein at a level which insures a liquid seal, manually, or automatically, by means of a 35 student lamp reservoir or otherwise. In the early stages of the incubation period, however, more moisture is required than at the later stages, and the lowering of the water level is therefore desirable after the said 40 early stages.

35 A series of air inlets 24 are provided in the trough above the water level, and an overflow pipe 25 prevents the water from rising above these inlets. At the bottom of the 45 trough a drain 26 is provided. The air inlets are protected, and the air admitted thereto regulated by shields 27 having a door 28 supported on friction hinges 29. The rod 30 running through the hinges and fixed to the upper edge of the door 28 forms a common 50 hinge pin. The door may be opened and closed to any desired extent, by means of the knob 31 and on account of the friction in the 55 hinges will remain in any position to which it may be moved. In this manner provision is 60 made for the careful and accurate regulation of the admission of air to the incubator. The heater pipe 16 is partly surrounded by the 65 water in the trough, and therefore heats and vaporizes the same. Its upper half, which is 70 above the water level, acts to heat the air admitted through the air intakes 24, which air 75 must pass over the upper surfaces of the pipe 16 and over the upper surface of the water 80

before passing upwardly into the incubating compartment. It will be seen, therefore, that all air admitted to the interior is first heated and moistened, and that the temperature of the air thus supplied approximates the temperature in the interior. Owing to its dependence upon contact with the heating pipe 16, for its temperature, however, it will be given a temperature slightly lower and will rise in the interior, and rise in temperature, carrying with it moisture from the trough and thus supply the desired volume of air at the proper temperature and at a proper rate to keep the interior atmosphere fresh and slightly humid and force out the air and other gases in the incubating chamber through the top ventilator 14.

Experience has demonstrated that the ideal conditions for incubation approach as closely as possible to the natural conditions produced by a fowl sitting on the eggs, which involve a certain degree of humidity, a constant temperature and a slow circulation of air with ventilation to carry off carbon dioxide generated by the eggs, and other impurities. This ideal condition is approximated by the present apparatus, and once it is properly regulated, these conditions will be maintained automatically throughout the period of incubation.

In order to still further regulate the admission of fresh heated and moistened air, and raise it to the temperature of the interior, a series of tubes 32 extending upwardly into the interior from a plate 33 covering the trough is provided, and the lower ends of these tubes are adapted to be opened and closed to a greater or less extent by a shutter 34 operated by a handle 35. Markings on the rod 36 for supporting and operating the shutter or other devices may be employed if desired to indicate the position of the openings 37 in the shutter and to show whether they register wholly or partly, and to what extent with the bottom ends of the tubes 32.

The incubator box has hinged doors 38, carrying the windows 3 and 4, secured in closed position by the latches 39, giving access to the egg shelves 40. Other details of construction may be added to those described and shown, and the details shown and described may be varied and some of them omitted without departing from the scope of the invention.

55 I claim:

1. In an incubator, the combination of a box or housing enclosing an incubating compartment, a heat generating device exterior thereto, a heat conduit extending from said generator into and through the upper part of said compartment, a conduit extending from said first-named conduit to the lower part of the incubator, a moistening device comprising a liquid holding vessel provided with controlled air inlets and air outlets to

the eggs and means for limiting the maximum level of water therein, in the lower part of said incubator, said second conduit extending into said vessel and having a horizontally disposed portion in the interior thereof, partly above and partly below said liquid level. 70

2. In an incubator, the combination of a box or housing enclosing an incubating compartment, a heat generating device exterior thereto, heat conduits extending from said generator into and through the upper part of said compartment, a conduit extending from said first-named conduits to the lower part of the casing, and a moistening device comprising a water pan with controlled air inlets and outlets into which said second conduit extends, said outlets permitting air to pass to the lower part of the compartment, and a tube for supplying liquid to said moistening device extending to the exterior of the casing and to a point above the liquid level in said device. 75 80 85

3. In an incubator, the combination with an incubator compartment of a moistener comprising a liquid container, a heating conduit extending thereinto, air inlet and controlling devices for admitting and controlling air to said moistener and means for controlling the outflow of air from said moistener, said controlling devices constructed and arranged to admit outside air directly to said moistener. 90 95

4. In a device of the kind described, an incubating compartment, a housing therefor, a moistening device comprising a water vessel located below the same and outside said housing, means for controlling the maximum level of water in said vessel, said moistening device having air inlets above and in proximity to said level, means for regulating and controlling the passage of air through said inlets, means for controlling the passage of moistened air from said moistening device to said compartment and means for heating said compartment and the water in said vessel by fluid from a common source. 100 105 110

Witness my hand this 1st day of November, 1926, at the city of New York, State of New York, county of New York.
